CLAIM

The ornamental design for a door bin for a refrigerator or
freezer, as shown and described.

DESCRIPTION

FIG. 1 is a perspective view of a door bin for a refrigerator
or freezer according to an embodiment of our new design;
FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a rear perspective view thereof.

The broken lines represent environmental structure or
unclaimed portions and do not form a portion of the claimed
design.

The dotted lines represent the border between claimed and
unclaimed subject matter and do not form a part of the
claimed design.
